UNITED STATES PATENT OFFICE

154,849

DESIGN FOR A TOY TYPEWRITER

Henry C. Hertz, Jackson, Mich., assignor to The
Dial-Writer Company, a partnership

Application January 26, 1948, Serial No. 144,017

Term of patent 3½ years

(Cl. D34—15)

To all whom it may concern:

Be it known that I, Henry C. Hertz, a citizen of the United States, and a resident of Jackson, Jackson county, Michigan, have invented a new, original, and ornamental Design for a Toy Typewriter, of which the following is a specification, reference being had to the accompanying drawing, forming a part thereof.

In the drawing:

Figure 1 is a front perspective view of a toy typewriter, showing my new design; and

Figure 2 is a front elevation of the toy typewriter.

I claim:

The ornamental design for a toy typewriter, as shown.

HENRY C. HERTZ.
